UNITED STATES PATENT OFFICE.

STEPHEN PALMER, OF LANSINGBURG, NEW YORK.

DESIGN FOR A SASH-PULLEY CASE.

SPECIFICATION forming part of Design No. 22,026, dated November 29, 1892.

Application filed September 15, 1892. Serial No. 446,021. Term of patent 7 years.

To all whom it may concern:

Be it known that I, STEPHEN PALMER, a citizen of the United States, residing at Lansingburg, in the county of Rensselaer and State of New York, have invented and produced a new and original Design for a Sash-Pulley Case, of which the following is a specification, reference being had to the accompanying drawings, forming a part thereof.

10 Figure 1 of the drawings is an elevation of the interior of one-half of the case, which is composed of two supplemental sections. Fig. 2 is a front elevation of one-half of the case, and Fig. 3 is a similar view of the entire case.

15 The leading feature of the design is the configuration of the duplex parts including the semicircular recesses having the walls thereof cut in a central plane, as denoted by the line F, said section-line receding from the

20 front at F' in the part C², and each part is provided with two wings having each a semicircular recess in one edge, said wings projecting in the same straight line from oppo-

site ends of an apertured plate having one side edge straight and in line with the two wings and the opposite side edge inclined to the straight edge, making the plate wider at one end than at the other.

A are the wings projecting from the opposite ends of the plate B in the same straight line and in line with the straight edge B' of the plate. Each wing is provided in one edge with the semicircular recess A'.

C is the inclined edge of the plate extending from the narrow end C' to the wide end C².

D represents the aperture in the plate.

What I claim as new, and desire to secure by Letters Patent, is—

The design for a sash-pulley case herein shown and described.

In testimony whereof I have hereunto set my hand this 10th day of September, 1892.

STEPHEN PALMER.
